UNITED STATES PATENT OFFICE.

FRANK P. SMITH, OF HANOVER, PENNSYLVANIA, ASSIGNOR OF ONE-HALF TO SMITH LYRA-
PHONE COMPANY, A CORPORATION OF WEST VIRGINIA.

AUTOMATIC ATTACHMENT FOR PIANO-PLAYERS.

No. 907,707.

Specification of Letters Patent.

Patented Dec. 22, 1908.

Application filed September 23, 1905. Serial No. 279,764.

To all whom it may concern:

Be it known that I, FRANK P. SMITH, a citizen of the United States, residing at Hanover, in the county of York and State of Pennsylvania, have invented a new and useful Improvement in Automatic Attachments for Piano-Players, of which the following is a specification.

My invention relates to improvements in automatic attachments for piano-players.

Among the objects of the invention are, to provide an expression bar consisting of a plurality of sections adapted to be operated in part or as a whole to control the touch of the key-levers; to provide an independent lever for controlling each section of the expression bar; to provide a lever adapted to be moved sidewise to control the speed of the take-up roller and also adapted to be pushed in to disconnect the take-up roller from its source of propulsion for temporarily stopping the travel of the music-sheet, and to arrange the lever for controlling the tempo and stop in close proximity with the levers for controlling the sections of the expression bar, whereby the expression, tempo, and hold may all be effected with one hand.

The invention consists of the new and novel parts and combination of parts hereinafter more fully set forth in the specification and pointed out in the claims.

In the accompanying drawings, Figure 1 is a side elevation of the upper part of a piano-player, showing my invention applied thereto. Fig. 2 is a detailed plan view of the expression bar and the operating levers, the two end sections being broken away. Fig. 3 is a detailed plan view of the tempo and hold lever. Fig. 4 is a detailed front view showing the expression levers and the tempo and hold lever. Fig. 5 is a detail, in bottom plan view, of portion of the wind chest and its attached operating wires and pneumatics.

The keyboard-operating devices comprise a series of levers 1, 2 and 3, and as such levers are the same throughout the entire set of keyboard-operating devices I have shown in the drawings one set thereof only. The levers 1 are suitably supported from the casing of the apparatus and are held to their normal position by the springs 4. Each of said levers is pivoted at about its center and adapted at one end to engage the keys of the

piano. The other ends of the levers 1 rest upon the levers 2, and the under sides of levers 2 are connected to levers 3 by thin flat pieces of spring metal 5. Secured to the lower ends of levers 3 and depending therefrom are curved arms 6, of wire or other suitable material, and said arms 6 terminate in heads 7. The series of levers 1, 2 and 3 as thus constructed and jointed together I will herein designate as "composite fingers", and they will hereinafter be so referred to as such.

Within the casing of the apparatus is suitably supported a longitudinal bar 8, having an inclined surface 9, and upon this inclined surface 9 there are secured a series of head-blocks 10, equal in number to the number of composite fingers. To the upper end of these head blocks 10 the levers 3 of the composite fingers are pivoted, as at 11, and which levers 3 normally rest upon said head-blocks. To the lower ends of the head-blocks 10 are pivoted the levers 12 which latter are operated by the puppets 13, arranged in suitable guides 14, the upper ends of said puppets being connected with rock-wires 15 arranged below and in line with the pneumatics 16 of the wind-chest 17. Loosely hung to the levers 12, as by pivots 18, are the shoe-levers 19, carrying at their lower ends the shoes 20, which latter are adapted to be brought into contact with the revolving cylinder 21 for the purpose of operating the composite fingers.

The expression bar is constructed of a plurality of sections 22, 23 and 24 supported by means of spring hinges 25 from an upright extension of the bar 8 and overhang the levers 2 of the composite fingers and are normally held above said levers by their spring hinges, and the said sections of the expression bar are connected by wires 26, 27 and 28 to their respective expression levers 29, 30 and 31 which latter extend to the front of the casing in convenient reach of the operator. Thus it will be seen that by raising any of said levers vertically its respective section of the expression bar will be brought closer to the levers 2 and the flexure of the connection between the levers 2 and 3 will be reduced and a more direct action of the lever 3 to the lever 1 will be produced, and a louder tone obtained. By having the expression bar made of a plurality of sections each connected to an independent lever, the said bar can be operated in part or as a whole

to control the touch of the levers 1. By this means it will be observed that expression in a piece of music can readily be produced by simply manipulating the expression levers at the proper time.

5 Just above the expression levers 29, 30 and 31, and in close proximity thereto, I provide a tempo and hold lever 32 pivoted at one end of a bell-crank lever 33, which latter is fulcrumed at 34 to the wind chest. The 10 tempo and hold lever 32 is connected to a wire 35 which leads to the mechanism for varying the speed of the take-up roller, whereby when the said lever 32 is moved to one side the speed of the take-up roller, and consequently the music sheet, is increased, and when moved to the opposite side the speed of the take-up roller is diminished. The bell-crank lever 33 is also connected to a 15 wire 36 leading to the mechanism for driving the take up roller, and adapted, when the lever 32 is pushed in to disconnect the take-up roller from its source of propulsion for temporarily stopping the travel of the music sheet. Thus it will be seen that by the side-wise movement of the lever 32 the tempo, or time, is controlled, and by pushing in said lever short stops or pauses in the music being played may be produced.

20 30 By arranging the levers 29, 30 and 31 in close proximity to the lever 32, it will be seen that the expression, tempo, and hold may all be readily controlled by one hand; the thumb resting in the lever 32 and three 25 fingers under the levers 29, 30 and 31.

Having thus described my invention, what I claim is:

1. In an automatic attachment for pianos, the combination with the take-up roller and 35 means for driving same, of a lever 32, a bell-crank lever 33 connected at one end to the lever 32, means connecting the other end of the

bell-crank lever 33 with the driving mechanism for the take-up roller for disconnecting the latter from its source of propulsion, and 45 a rod 35 connecting the lever 32 with the means for varying the speed of the take-up roller.

2. In an automatic attachment for pianos, the combination of an expression bar consisting of a plurality of sections, levers for controlling the sections of the expression bar, a lever 32 arranged in close proximity to the expression levers, a bell-crank lever 33 connected at one end to the lever 32, means connecting the other end of the lever 33 with the driving mechanism for the take-up roller for disconnecting the latter from its source of propulsion, and a rod 35 connecting the lever 32 with the means for varying the speed 50 55 60 of the take-up roller.

3. In an automatic attachment for pianos, the combination with the take-up roller and means for driving same, of the levers 1, 2 and 3, an expression bar consisting of a plurality 65 of sections extending across the levers 2, an independent lever for controlling each section of the said expression bar, a lever 32 arranged in close proximity to the expression levers, a bell-crank lever 33 connected at one 70 end to the lever 32, means connecting the other end of the lever 33 with the driving mechanism for the take-up roller for disconnecting the latter from its source of propulsion, and a rod 35 connecting the lever 32 75 with the means for varying the speed of the take-up roller.

In testimony whereof I have signed my name to this specification in the presence of two subscribing witnesses.

FRANK P. SMITH.
